UNITED STATES PATENT OFFICE.

ERSKINE EBENEZER BOYCE, OF CHARLOTTE, NORTH CAROLINA, ASSIGNOR TO MILL DEVICES COMPANY, OF DURHAM, NORTH CAROLINA, A CORPORATION OF NORTH CAROLINA.

KNOTTER DEVICE.

Application filed May 6, 1924. Serial No. 711,401.

My invention relates to an improvement in knotters, and with respect to its more specific features, to machines for forming weavers' knots.

5 An object of the invention is to provide a new and improved connection between the means for positioning the strands with relation to the tying bill, and the common operating means for the said positioning means and the bill.

In knotters of the character forming the subject matter of application of Britton E. Byrd, Serial No. 538,889, filed February 24, 1922, the strands to be knotted are mechanically positioned with relation to the tying bill, prior to the operation thereof, and a common means is provided to operate the bill and the positioning means in sequence. The connection between the positioning means and the common operating means is maintained throughout the operation of the bill, and such connection is effective in reverse movement of the bill, to loosen the positioning means, which during the operation 25 of the bill act as tensioning means for the strands.

In the present invention the connection is such that the positioning means is released from the operating mechanism prior to the 30 operation of the bill, and is positively locked from movement reversely until the bill is in its normal inoperative position.

In the drawings, forming a part hereof:

Fig. 1 is a side view of the improved 35 knotter.

Fig. 2 is a front view.

Figs. 3, 4 and 5 are side views with the near frame plate removed, showing the different positions of the parts during the formation of a knot.

Figs. 6, 7, 8, 9, and 10 are enlarged perspective views of the knot tying and strand positioning means, showing the several steps in the operation of tying the weaver's knot.

45 In the present embodiment of the invention, the improved knotter comprises a suitable frame composed of side plates 10 and 11, which are connected together in spaced relation, by screws 12 and 13, and spacing members to be described. The screw 13 con-

ncts the plates to a handle member 14, adapted to be grasped in the palm of the hand, and a strap 15 is connected with the ends of the handle member for engaging the back of the hand to hold the device in place. 51

One of the spacing members is a substantially U-shaped bracket having arms 16 and 17, which extend between the plates 10 and 11. The arm 17 has lugs 18, which engage slots in the plates 10 and 11 to prevent displacement of the spacing member, and the said arm forms a front bearing for the tying bill shaft, to be described. The rear bearing is in a housing plate 19, arranged between the plates 10 and 11 at the rear thereof and closing the space between the plates at this point. The housing plate has laterally extending lugs 20, which engage slots in the plates 10 and 11 to prevent displacement thereof. 70

75 The tying bill includes a shaft 21 which is journaled in the arm 17 of the U-shaped bracket, and is supported at its rear end by a screw 22 threaded through the housing plate 19. The rear end of the shaft 21 is pointed, and engages an axial recess in the screw 22, and the movement of the shaft toward the U-shaped bracket is limited by a collar 23 rigid on the shaft. The screw 22 is held in adjusted position by a lock nut 24, and that portion of the shaft between the pointed end and the collar 23 is flattened, as shown, and the intermediate portion thereof is helical.

80 The tying bill comprises a clamping bill 25, a cutting bill spring 26, and an intermediate clamping and shearing jaw 27, the said jaw being pivoted between the bill and the spring on a pivot indicated at 28. The tying bill passes through a circular opening 90 in the arm 16 of the U-shaped bracket, and the said opening is eccentric to the bill. The jaw 27 has a wing portion 29, which by its engagement with the opening during the rotation of the bill, operates the shearing and 95 clamping jaw.

Mechanism is provided at each side of the bill for supporting a pair of strands to be knotted in proper relation with respect to the bill. Each of the plates 10 and 11 is 100

deeply notched at its front end, and on the upper edge, to form in each plate a pair of seats for the two strands. When the strands are to be knotted, they are laid in 5 the seats, extending transversely of the frame, and with one strand on each side of the bill. The positioning means comprises a pair of rocking members 30 and 31 pivoted to the respective side plates 10 and 10 11 of the notches above mentioned. Each of these rocking member has a notch 32 and 33, respectively, serving as a holder to engage the outermost strand when the members are rocked to move said strand inward- 15 ly above the inner strand. The members are rocked by links 34 and 35 respectively, which are mounted on the outer faces of the plates 10 and 11. Referring to Fig. 1 es- 20 pecially, it will be noticed that the extrem- 25 ity of each plate 10 and 11 at the front thereof, is offset outwardly, and the links 34 and 35 pass through slots in the connections between the offset portions and the bodies of the plates. The rear end of each link is thus on the outer face of the adjacent plate, 30 while the rocking members and the front ends of the links are on the inner faces of the plates.

The ends of the links are connected by 35 a shaft or rod 36 which passes through slots 37 in the plates, and by means of this rod or shaft, the links are connected with radial arms 38 on a shaft 39, journaled between the plates 10 and 11, and near the top of 40 the frame. These arms 38 are rigid with the shaft, and it will be evident that when the shaft is rocked the links will be recipro- 45 cated to rock the rocking members. Each link has an upstanding finger 40 for the link 40, and 40^a for the link 35 adjacent to the notch of the side plate, and at the inner side thereof, and the said fingers are positioned to engage the inner strand resting in the 50 notch seats to move said strand outwardly beneath the outer strand, at the same time that the said outer strand is moved inward- 55 ly. The finger 40^a is notched on its outer face, as shown at 40^b to prevent the strand slipping over the finger during the out- 60 ward movement thereof.

The bill is rotated by means of a lever 41 pivoted on the screw 13, before mentioned. The upper end of the lever is forked, and the arms 42 and 43 of the fork 55 extend on opposite sides of the shaft 21, before mentioned. The arms are spaced a less distance than the width of the flattened shaft, and it will be obvious that when the lever is swung on the screw 13, the arms will 60 be moved longitudinally of the shaft, and will cause the shaft to be rotated through their engagement with the helical portion thereof.

The mechanism for positioning the

strands with relation to the tying bill prior 65 to the operation thereof, constituted by the rocking members and the links, is operated through a cam 44 rigid with the arm 42 of the lever 41. This cam as shown ex- 70 tends forwardly from the lever, and is deeply notched near its forward end, on its upper edge, as shown at 45, and in front of the notch the cam is extended upwardly to form a nose 46 for engaging the shaft 36 before mentioned, when the lever is swung to move 75 the fork arms rearwardly. The forward end of the notch 45 is so contoured that when the fork arms move rearwardly, the shaft 36 will be moved rearwardly in the slots 37, to restore the positioning means for 80 the strands to the normal position shown in Fig. 1. The upper edge of the cam 44 be- 85 hind the notch 45 is arc-shaped, and is con- 90 centric with the screw 13. The radius of the arc-shaped edge is such that while the edge is moving in contact with the shaft 36, the said shaft will be held at the forward ends of the slots 37. The shaft cannot move rearwardly in the slots, until the notch 45 comes into register therewith, at which time 95 the nose 46 will engage the shaft and will constrain it to move into the notch. The lever 41 is returned to the normal position, shown in Fig. 3, by means of a spring 47 encircling the screw 13, engaging at one end 100 of the frame and at the other end the lever.

With the parts in the position of Fig. 3, and with the two strands lying in the notches of the plates 10 and 11, and on op- 105 posite sides of the tying bill, when the lever 41 is moved toward the handle 14, the shaft 36 will first be moved forwardly in the slots 37 to the position of Fig. 4. The rear wall of the notch 45 is so contoured, that this movement of the shaft will result from the 110 swing of the cam. At this moment the shaft passes out of the notch and onto the arc- 115 shaped upper edge of the cam. During the further movement of the lever 41 to operate the tying bill, the shaft 36 will be positively locked in the position shown in Figs. 4 and 5, by the cam. The positioning means is in effect disconnected from the operating means therefor, that is the lever 41, during the entire operation of the tying bill, and 120 is not again connected with the lever, until the parts are moving into the position of Fig. 4 on the return movement of the lever. At the moment when the return movement of the tying bill is complete, the shaft will 125 be engaged by the nose 46 and will be again connected with the lever 41.

The arrangement of the helical portion of the shaft 21 is such that the fork arms of the lever 41 may move for a certain distance 125 from rest position, without effecting a ro- 130 tative movement of the tying bill. This movement is of sufficient extent to permit the

lever to operate the positioning means at the commencement of a knotting operation before rotative movement is imparted to the bill.

The operation of the mechanism just described is as follows: In order to knot the strands, they are laid alongside each other in the holders, that is the notches, of the plates 10—11. The lever 41 is now swung 10 on its pivotal connection 13, the cams swing downward toward the position of Fig. 4 forcing the shaft 36 to the front ends of the slots 37, and moving the links 34 and 35 longitudinally. The fingers 40 of the said

15 links engage the inner strand α , and push the same outwardly. At the same moment the rocking members engage the outer strand α^1 and lift it over to the inner side of the inner strand, Fig. 7. The strands are thus 20 crossed on opposite sides of the bill and at the completion of the crossing movement the rocking members and the links which lightly clamp the strands between them, act as tensioning members for the strands. Further 25 movement of the lever 41 rotates the tying bill, which in its rotation connects the two strands with a weaver's knot, Fig. 10, an intermediate formation being shown in Fig. 8.

30 The blade 27 of the tying bill cuts one of the strands, and the other is cut by an auxiliary blade 48 carried by an arm 47 journalled on the shaft 39 before mentioned. This arm depends in front of the arm 16 of 35 the U-shaped bracket at the right of the tying bill, and the blade is on the opposite side of the arm from the tying bill. A cam arm, composed of portions 52 and 53, is provided for operating the arm 47, and the said

40 portions, which extend on opposite sides of the shaft 39, are rigid with the arm 47. The fork arm 43 of the lever 41 has a roller engaging the under edges of the portions 52 and 53 when the lever 41 is rocked. The 45 arm 52 is so arranged that while the roller is in engagement therewith, the arm 47 is in the position of Fig. 4. When, however, the roller engages the portion 53 of the cam arm, the arm 47 is abruptly rocked into the 50 position of Fig. 5, lifting the blade into engagement with the other strand, and severing the same.

The knot is now loosely tied, and it must be stripped from the bill to complete the 55 formation thereof and strained to tighten the knot. The stripping and straining mechanism is carried by the arm 47 and comprises a stirrup 51, one of the arms of which is connected to the depending portion 60 of the arm 47. A screw 49 passes through the stirrup arm and through the upper end of the blade 48, the said blade being between the stirrup arm and the arm 47. The blade and the stirrup arm have a series of

registering openings extending transversely 65 thereof, for receiving a screw 50 passed through the arm, the blade and the stirrup, in the opposite direction to the screw 49. By engaging the screw with different openings of the series, the angular position of 70 the blade and of the stirrup with respect to the arm 47 may be varied. The body of the stirrup extends transversely of the bill below the same, as shown in Fig. 2, and the free arm thereof is at the opposite side 75 of the bill from the arm 47. When the arm 47 is swung upward, the blade cuts the uncut remaining strand, and the free arm of the stirrup engages the strands on the other side of the bill, stripping the knot 80 from the bill, and straining the knot to tighten the same. At this time the strand which has been cut by the tying bill is clamped between the jaws, and the stripping of the knot from the bill draws the knot 85 tight before the end of the strand is pulled from the bill. The free arm of the stirrup is notched, as shown at 55, to prevent slipping of the threads therefrom during the 90 stripping operation.

In order to prevent catching of the strands in the operating parts of the mechanism a shield plate 54 is arranged on the plate 11, extending from behind the shaft 39, to the beginning of the offset portion 95 of the said plate.

While the invention is shown in a preferred form, it will be apparent that changes and modifications may be made in the structure disclosed, without departing from the 100 spirit of the invention as defined in the appended claims.

What I claim is:—

1. In a device of the class described, a 105 tying bill, rocking members to position the strands for knotting prior to the operation of the bill, means to operate the members and the bill in sequence, said means released from the rocking members during the operation of the bill.

2. In a device of the class described, a 110 tying bill, rocking members to position the strands for knotting prior to the operation of the bill, means to operate the members and the bill in sequence, said means released from the rocking members during the operation of the bill, and means controlled by the operating means to positively lock the rocking members from movement during the operation of the bill.

3. In a weaver's knot tying mechanism, in combination with a rotary tying bill and mechanism for crossing the strands on opposite sides of the bill, said mechanism including a laterally movable shaft, means for moving the shaft in one direction, and for rotating the bill in sequence, including 125 an oscillatable cam having a notch normal-

ly engaged by the shaft and out of which it is moved to operate the strand crossing mechanism at the beginning of the oscillation of the cam in one direction, and a concentric portion for engagement by the shaft when out of the notch to lock the crossing mechanism from movement, the cam having

means to engage the shaft and return it to the notch at the end of the oscillation of the cam in the other direction. 10

Signed at Charlotte, in the county of Mecklenburg, and State of North Carolina this third day of May A. D. 1924.

ERSKINE EBENEZER BOYCE.
